UNITED STATES PATENT OFFICE.

FREDERICK REINHARD, OF JERSEY CITY, NEW JERSEY, AND PIETRO GENCHI, OF NEW YORK, N. Y.

DESIGN FOR A HARP.

No. 38,242.

Specification for Design.

Patented Sept. 18, 1906.

Application filed July 13, 1906. Serial No. 326,153. Term of patent 14 years.

To all whom it may concern:

Be it known that we, FREDERICK REINHARD, a resident of Jersey City, county of Hudson, State of New Jersey, and PIETRO GENCHI, a resident of the borough of Manhattan, city, county, and State of New York, citizens of the United States, have jointly invented a new, original, and ornamental Design for a Harp, of which the following is a specification.

Figure 1 of the accompanying drawings is a face view of the harp, showing our new de-

sign. Fig. 2 is a face view from the opposite side of said harp, and Fig. 3 is an edge view thereof.

We claim—

The ornamental design for a harp as shown.

FREDERICK REINHARD.
PIETRO GENCHI.
